CLAIM

The ornamental design for an electromagnetic driving pilot valve, as shown and described.

DESCRIPTION

FIG. 1 is a front, top, and left side perspective view of an electromagnetic driving pilot valve showing the new design. FIG. 2 is a rear, bottom, and right side perspective view thereof.

FIG. 3 is a front elevational view thereof, the rear elevational view being a mirror image of the front elevational view.

FIG. 4 is a top plan view thereof.

FIG. 5 is a bottom plan view thereof.

FIG. 6 is a left side elevational view thereof; and,

FIG. 7 is a right side elevational view thereof.

The broken lines depict portions of the electromagnetic driving pilot valve that form no part of the claimed design.

1 Claim, 7 Drawing Sheets
